(57) CLAIM

The ornamental design for a basketball, as shown and described.

DESCRIPTION

FIG. 1 is a top, front, and right side perspective view of the basketball, showing the new design;

FIG. 2 is a front view of the basketball;

FIG. 3 is a rear view of the basketball;

FIG. 4 is a left side view of the basketball;

FIG. 5 is a right side view of the basketball;

FIG. 6 is a top view of the basketball; and,

FIG. 7 is a bottom view of the basketball.

The dash-dash-dash lines are included for the purpose of illustrating portions of the basketball that form no part of the claimed design. The white color in the figures adjacent and between the dash-dash-dash lines forms no part of the claimed design.

1 Claim, 7 Drawing Sheets
